UNITED STATES PATENT OFFICE

GEORGE STIEGLER, OF CINCINNATI, OHIO

MARKING MACHINE

Application filed May 24, 1930. Serial No. 455,392.

My invention relates to marking machines designed particularly for the marking of articles in laundries and the marking of manufactured goods with style and lot numbers, and

for many other uses which will be apparent.

The usual laundry marking machine is a large, cumbersome apparatus, whereas, according to my invention, I have constructed my device similarly to a time stamping or numbering machine wherein a handle is depressed so as to permit the depressing of a system of dials by hand in a small portable frame.

It is the object of my invention to provide a bodily movable dial system consisting of a plurality of dials in connection with which I provide means for locking and aligning the dials together when in use, and permitting the changing of any dial or dials by a releasing of the dial aligning members, there being one for each dial. I provide an inking device which, during the depression of the dial system, swings an inking pad into contact with the dial and then moves the inking pad out of the way, and I provide means whereby the pressure of the inking device against the dial can be controlled, so that heavy marking or light marking can be accomplished. Certain features of my mechanism are novel and useful irrespective of the type of printing or marking member that is employed.

My device is very easily assembled and disassembled, and consists of a small number of parts, and is easy to operate and keep in repair.

I accomplish my objects by that certain construction and arrangement of parts of which a typical example is illustrated and described, and the novelty of which is set forth in the appended claims.

In the drawings:—

Figure 1 is a side elevation of the complete device.

Figure 2 is a front elevation thereof.

Figure 3 is a side elevation with the housings and frame partially broken away, taken from the opposite side of Figure 1.

Figure 4 is a detail showing the inking pad in contact with the marking dials.

Figure 5 is a similar view showing the pad

in its holder swung out of the way during the printing or marking operation.

Figure 6 is a sectional detail showing the mounting of the dial system.

Figure 7 is a detail section taken on the line 7—7 of Figure 6, whereas Figure 6 is a section taken on the line 6—6 of Figure 7.

Figure 8 is a perspective of the dial shaft.

Figure 9 is a perspective of one of the dials.

Figure 10 is a perspective of one of the friction discs.

Figure 11 is a rear elevation of the inking pad structure.

Figure 12 is a section on the line 12—12 of Figure 11.

Figure 13 is a section on the line 13—13 of Figure 11.

Figure 14 is a side elevation of the movable dial frame showing the spring dog which operates the inking device.

Figure 15 is a rear elevation of the same parts.

Figure 16 is an enlarged section taken on the line 16—16 of Figure 15.

The structure is formed of a U-shaped frame 1 having a base 2 which is applied over the article to be marked, which has an opening 2a through which the desired dial face projects in marking a piece of fabric or the like. A tube 4 is secured to the top of the U-shaped frame through which tube passes an operating rod 5 of the machine. The upper end of the operating rod is equipped with a handle 6 which telescopes over the tube 4, and a spring 7 is housed within the tube 4 and the handle 6 and serves to press the handle upwardly to the position shown in Figure 3.

Within the main U-shaped frame is the dial carrying frame shown in Figures 14 and 15, which consists of a U-shaped piece having side plates 8—8 and a top portion 9. The upper portion of this frame at the rear is closed by a transverse wall 10. The side plates have projections 11 which serve to mount a pin 13 which pivotally supports a series of pawls 14. The pawls have handles 15 whereby they are operated, and each pawl has a spring 16 connected so as to draw the lower end of the pawls inwardly of the mech-

anism, these springs 16 being connected to a pin 17 extending across the upper end of the frame 8. Secured on one side 8 of the dial carrying frame is a stud 18 which slides in a groove 19 in the frame 1. The other side of the frame 1 has a vertically extending slot 20 through which the dial shaft projects. The dial shaft shown in detail in Figure 8 has a slotted shaft portion 21, a collar 22 which engages the inner face of the frame 1, and a head 23 which engages the outer face of the frame 1 (Figure 6). The shaft 21 passes through and is supported in the apertures 24 in the sliding dial frame 8. Set alternately on the shaft 21 between the sides of the sliding dial frame are numbering or marking wheels or dials 25 and friction washers 26. The friction washers have internal keys 27 which engage the grooves or splines 28 in the dial shaft. The dials are so located that they are engaged each by one of the pawls 14, and the type faces 29 of the dials are considerably projected from the main body of the dials so as to act as teeth with spaces 30 between them in which the pawls engage.

As so far described, it is evident that if the operator pushes downwardly on the handle 6 the frame 8, 9, carrying the dials and pawls will be depressed in the frame 1 and a selected type face on the dials will be impressed upon the article to be marked. Upon the release of the handle the dials and their frame will move upwardly to starting position. To change any dial its pawl its elevated by pressing inwardly on its handle 15 and the head 23 of the dial shaft revolved, which will frictionally move the selected dial around. When the dial has been brought to the desired position for marking the pawl is released and will hold this dial against further movement while other dials are being adjusted, and in addition will line up the adjusted dial with the remainder of the dials.

The inking mechanism

The inking mechanism is mounted on a flanged plate 31 (see Figures 11 and 12), which plate has ears 32 whereby it is secured by pivot screws 33 in the upper end of the U-shaped frame 1. A leafed spring 34 secured to the top of the frame 1 engages the plate 31 and holds it in position against the side of the U-shaped frame 1, from which position the plate 31 is swung during the operation of the machine, as shown in Figure 5. On the rear or outer face of the plate 31 are secured a pair of strips 35 which form a guideway for a bar 36, the lower end of which is provided with rack teeth 37. The bar is secured to a plate 38 which lies in the guideway formed by the part 35, the plate 38 being backed by the plate 39 that lies in a slot in the plate 31. These parts are best shown in Figure 13. A spring 40 secured

to a stud 41 passing through the plate assembly 36, 38, and 39, serves to hold a rack bar in its upper position.

A shaft 42 mounted in projecting arms 43 of the flanged plate 31 is fixedly secured to a yoke 44. The yoke 44 carries an ink pad 45 which is rocked into engagement with the descending dials when the shaft 42 is rocked. A sector gear 46 at the center of the shaft 42 is engaged by the rack bar so that when the rack bar descends it will rock the shaft 42.

Secured on the inner face of the plate 31 is a slanting finger 47 which strikes the rear edge of the dial frame resulting in rocking the plate 31 and the parts assembled thereon entirely out of the way of the descending dial system.

In order to push downwardly on the rack bar, means are provided on the back plate 10 of the sliding dial frame for engaging the upper end of the sliding rack bar assembly. To this end the members 38 and 39 terminate flush with each other as at 48, where they are engaged by a spring dog 50 which will now be described.

Referring to Figures 14, 15 and 16, I secure to the back of the dial frame a casting having slotted lugs 49-49 which are interspaced to act as a guide for the bevel edged dog 50. This dog is mounted on a bolt which slides in a boss 51 of the casting and is equipped with nuts 52. A spring 53 lying between the dog and the boss tends to push the dog outwardly. By turning down the nuts 52 the position of the dog and the spring tension urging it outwardly can be adjusted. Also, any desired spring can be employed and the position of the dog 50 regulated by means of the nuts 52. In order to guide the dog firmly, a pair of pins 54 are inserted laterally into it, and these pins slide in the slotted lugs 49.

The dog engages the end 48 of the rack bar mounting so that as the dial system is depressed the dog will push downwardly on the rack bar, thus causing the inking pad to swing into engagement with the descending dial. When the engagement is established and the operator continues to press down on the dial system, the dog 50 will be forced out of the way, thus permitting the rack bar to move upwardly and by means of the rack and gear, causing the inking pad to be swung out of the way of the dials. When this is accomplished the finger 45 contacts with the dial frame which moves the entire inking device out of the way as the marking impression is made.

By adjusting the tension of the spring 53, and adjusting the position of the dog 50, the force with which the inking pad is brought up against the dial can be regulated as is evidenced.

Upon spring return of the marking dials

to their original position, the dog 50 will again engage over the end 48 of the rack bar mounting and the machine will be ready for another operation.

5 In practice the machine can be operated as rapidly as the operator can press down and release the handle 6. The adjustment of the dials is simple and easy, and the inking pad is normally out of contact with the dials 10 instead of being in contact with them, as in the usual time stamping or numbering machine. The locking device for the marking dials serves to keep them in alignment, and the friction method of adjusting the dials is 15 such that very little effort is required.

Having thus described my invention, what I claim and desire to secure by Letters Patent of the United States is:

1. In a marking machine, a frame, a marking element reciprocating in said frame, an inking device for said marking element comprising a mounting member secured to the frame, an inking pad on the mounting member, means for normally retaining the inking pad out of contact with the marking member, means for moving the inking pad into contact with the marking member and a device on the marking member for operating and then releasing the inking pad moving 30 means during the movement of the marking member.

2. In a marking machine, a frame, a marking element reciprocating in said frame, an inking device for said marking element comprising a mounting member secured to the frame, an inking pad on the mounting member, means for normally retaining the inking pad out of contact with the marking member, means for moving the inking pad into 40 contact with the marking member, a device on the marking member for operating and then releasing the inking pad moving means during the movement of the marking member, said mounting member being movably held on the frame and inter-engaging means between the marking member and the mounting member to rock the latter out of the path of the former.

3. In a marking machine, a frame, a marking element reciprocating in said frame, an inking device for said marking element comprising a mounting member secured to the frame, an inking pad on the mounting member, means for normally retaining the inking pad out of contact with the marking member, means for moving the inking pad into contact with the marking member and a tension retained device on the marking element for operating the inking pad moving means 55 during the movement of the marking element, the inking pad moving means comprising a rack and pinion, said tension device on the marking member arranged to engage the said rack.

4. In a marking machine, a frame, a mark-

ing element reciprocating in said frame, an inking device for said marking element comprising a mounting member secured to the frame, an inking pad on the mounting member, means for normally retaining the inking pad out of contact with the marking element, means for moving the inking pad into contact with the marking element and a tension retained device on the marking element for operating the inking pad moving means during the movement of the marking element, the inking pad moving means comprising a rack and pinion, said tension element on the marking element arranged to engage the said rack, said tension element being a spring projected tapered dog.

5. An inking device for marking machines comprising a frame, a rack slidably held in said frame and having a portion exposed for engagement by an operating finger, a marking pad rotatably mounted and having a pinion connected to effect its rotation, said rack engaging said pinion and a spring for holding the rack normally in position to hold the inking pad out of operative relation.

6. An inking device for marking machines comprising a frame, a rack slidably held in said frame and having a portion exposed for engagement by an operating finger, a marking pad rotatably mounted and having a pinion connected to effect its rotation, said rack engaging said pinion, a spring for holding the rack normally in position to hold the inking pad out of operative relation, said frame having pivotal mounting means, a spring for holding said frame in position and means to stop the pivoted movement of said frame against the spring pressure applied thereto.

7. In a marking machine, a manually movable marking element, an inking pad, and means operated by the marking element during its marking stroke to project the pad into inking contact therewith, said means including a member on the marking element which gives way at the period of contact of the pad.

8. In a marking machine, a support, a marking device movable on said support, an inking device comprising a frame mounted to swing on said support, and inking means mounted to swing on said frame, means whereby said marking device swings said frame, and self-adjustable engaging means whereby said marking device swings said inking means relatively to said frame.

9. In a marking machine, a support, a marking device movable on said support, an inking device comprising a frame mounted to swing on said support, and inking means mounted to swing on said frame, means whereby said marking device swings said frame, and self-adjustable engaging means whereby said marking device swings said inking means relatively to said frame to cause pressure of said inking means against said marking means, said self-adjusting means

adjusting itself to a substantially inoperative position incident to a desired degree of said pressure.

- 5 10. In a marking machine, a support, a marking device movable on said support and comprising a movable frame and marking means with a plurality of marking faces, mounted on said frame for movement to present one or the other face for marking, and
10 15 20 25 30 35 40 45 50 55 60 65
detent means for said marking means at one side of said marking device, an inking device comprising a frame mounted to swing on said support at the other side of said marking device, and comprising inking means mounted to swing on said frame, means whereby said marking device swings said frame, and self-adjustable engaging means whereby said marking device swings said inking means relatively to said frame.
11. In a marking machine, a support, a marking device movable on said support, an inking device comprising a frame mounted to swing on said support, and inking means mounted to swing on said frame, teeth with which said marking means swings, and a slideable rack meshing with said teeth, means whereby said marking device swings said frame, and means on said marking device self-adjustably engaging with said rack, whereby said marking device swings said inking means relatively to said frame to cause pressure of said inking means against said marking means, said self-adjusting means adjusting itself to a substantially inoperative position incident to a desired degree of said pressure.
12. In a marking machine, a support, a marking device, an inking device comprising a pad, and gear means operated by the marking element during its marking stroke to project the pad into and then out of inking contact with said marking element.

GEORGE STIEGLER.
